UNITED STATES PATENT OFFICE.

HENRY HAYES AND BERTINE P. BONNELL, OF CHICAGO, ILLINOIS.

STEAM-GENERATOR.

SPECIFICATION forming part of Letters Patent No. 352,319, dated November 9, 1886.

Application filed April 20, 1886. Serial No. 199,470. (No model.)

To all whom it may concern:

Be it known that we, HENRY HAYES and BERTINE P. BONNELL, of Chicago, State of Illinois, have invented certain new and useful Improvements in Steam-Generators, of which the following is a specification.

The improvements relate to steam-generators designed and arranged for heating dwellings; and the object is to furnish an economical, durable, safe, and inexpensive apparatus for this purpose which can be easily operated by any unskilled person of ordinary understanding; and the invention consists in the combinations and arrangement hereinafter 15 more particularly described and claimed.

The accompanying drawings illustrate the invention. Figure 1 is a vertical section. Fig. 2 is a horizontal section on line *xx*.

A designates the boiler, which is a hollow cylinder, the central opening, *a*, of which at the upper part being only large enough to admit the fuel-magazine *B*; but the lower part is considerably expanded, so as to form a large fire-chamber, *a'*, around and below the lower 20 end of the fuel-magazine and fire-grate *C*, and surround the fire with a thin sheet of water, *c*, between the outer and inner plates of the boiler. The outer part of the boiler and the inner part, *a'*, as well as the top and bottom, 25 are made of good boiler-iron securely riveted together. Two or more rows of pipes, *a''*, connect the water-space above with the narrow space *c*, so as to afford a circulation of the water from the lower part to the upper part. Flue- 30 openings *D* are provided on opposite sides through the narrow water-space at the top of the fire-chamber for allowing the smoke and products of combustion from the fire to pass off.

E is a safety-valve of any ordinary construction, and *F* is a steam-pipe connecting with the steam-chamber at the top of the boiler above the water-line, for conveying the steam to the various radiators located at the points to be 35 warmed.

G is the steam-gage, and *G'* the water-gage, of ordinary construction.

H is a pipe through which the water-supply is admitted.

H' is an opening for a peep-hole, which is made large enough to put in kindling for start-

ing the fire, and provided with a door for closing it tightly at the outer end.

At the junction *c'* of the horizontal and vertical parts of the interior of the boiler-plates 55 a projecting ledge is formed at the bottom.

The fuel-magazine is made in two parts, the lower part, *b*, being made of cast-iron and having an outwardly-projecting flange, *b'*, at the top, adapted to rest on the ledge at the junction *c'*, and the upper part, *b''*, is made of sheet metal, and provided with a similar flange at the top adapted to rest on the edge of the top opening, and extends down for a short distance below the top of the lower part. The 60 object of thus constructing the magazine in two parts is to enable it to be easily taken out for repair or renewal of the lower part when burned out without removing the boiler from its place in the basement, the floor above, as 65 usually located, being not of sufficient height to admit of raising the magazine out of the boiler, if made in one piece. A cover, *B'*, is laid over the top of the magazine.

The boiler thus described is set in brick-work, *I*, with open space *I'* all around it, and having the flue-opening *D'* connected at the bottom of the open space, so as to cause the draft to pass downward around the outside of the boiler, as indicated by the arrows. An 70 outer jacket may be employed in place of the brick-work; but the latter is preferable.

The arrangement of the pipes and the narrow water-space completely surrounding the fire, with the flue-openings at the top of the 75 fire-chamber and at the bottom outer space, affords the utmost economy of fuel, and the fuel-magazine enables the fire to be kept up for considerable time without attention.

We are aware of the patent to Latimer, No. 90 316,274, of April 21, 1885, which shows a boiler having a water-jacket surrounding the combustion-chamber, and oblique water-pipes connecting the water-space near the lower part of the combustion-chamber with the water-space 95 above it. It also has a double row of flues through the water-jacket, located at a point in the combustion-chamber about midway of the length of the water-pipes, and doors in the outer shell registering with these flues, and an 100 air-chamber above the steam-chamber, and a common flue connected at the top of the air-

chamber, the object being to draw the caloric current away from the fuel-magazine and upward from the double row of flues. Our boiler differs from this in various respects. We use 5 only two flues, D, through the water-jacket, and place them on opposite sides of the combustion-chamber, and near its top we connect the common flue, D', at the bottom of the space around the water-jacket, and as low down as 10 the bottom of the water-jacket. With this location of the flues the heat rises to the top of the combustion-chamber, thence passes out, and thence a portion of it with the smoke is drawn downward to the bottom of the water-jacket all around on the outside. We do not 15 use doors in the outer shell registering with the flues, as they would let in more or less cold air and produce a cooling effect, nor have any air-chamber at the top, nor common flue 20 at the top of the generator. All of the heat that rises in the space outside of the boiler and between it and the brick wall above the flues D is confined there, instead of being drawn off by a flue connecting with this space from 25 above; nor does our construction leave an opening between the fuel-magazine and the central opening which communicates with the combustion-chamber; but the opening provided with the ledge at c, and having the 30 flange b of the lower section rested upon it, is effectually closed between the magazine and boiler at the top of the combustion chamber.

What is claimed is—

1. A steam-generator consisting of the boiler provided with the central opening, a, 35 having a projecting ledge at c', an enlarged opening in the portion below said ledge forming the fire-chamber, water-pipes a', connecting the water-space surrounding the fire-chamber at the sides with the water-space above it, two openings, D, near the top of and on opposite sides of the fire-chamber, the fuel-magazine B in separate sections b b', each provided with a flange, b', at the top, adapted 40 to rest on the top and on ledge at c' of the central opening, and the brick-work or outer covering, I, with space between it and the boiler, and common flue D', located at the bottom of said space, as and for the purpose 45 specified. 50

2. In a steam-generator, the fuel-magazine B, composed of separate sections b b', each provided with a flange, b', in combination with the central opening, a, of the boiler, provided with a ledge at c' for resting the flange 55 of said lower section upon, and having the flange of said upper section resting on its edge at the top, substantially as specified.

HENRY HAYES.
BERTINE P. BONNELL.
